UNITED STATES PATENT OFFICE.

FRANK L. CAPPs, OF NEWARK, NEW JERSEY.

DESIGN FOR A FRAME FOR PHONOGRAPH-MOTORS.

SPECIFICATION forming part of Design No. 26,491, dated January 5, 1897.

Application filed May 27, 1896. Serial No. 593,345. Term of patent 7 years.

To all whom it may concern:

Be it known that I, FRANK L. CAPPs, a citizen of the United States, residing at Newark, in the county of Essex and State of New Jersey, have invented and produced a new and original Design for Phonograph-Motor Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a perspective view of my newly-designed phonograph-motor frame, and Fig. 2 is a detail perspective view of a portion of the same.

The leading feature of the design consists in a phonograph-motor frame having an L shape in plan.

A indicates one arm of the newly-designed frame. B is another arm, disposed at right angles to the first, the two arms taken together presenting to view the L shape in general plan of the frame.

C is an offset of the frame. At one side of one arm and at one end of the other are serration-shaped protuberances.

What I claim is—

3° The design for a frame for phonograph-motors herein shown and described.

In testimony that I claim the foregoing I have hereunto set my hand this 22d day of May, 1896.

FRANK L. CAPPs.
